LOCKS FOR UPWARDLY ACTING DOORS

Earl L. Stroup, Hartford City, Ind., assignor to Overhead Door Corporation, Hartford City, Ind.

Application November 25, 1955, Serial No. 548,828

7 Claims. (Cl. 292—244)

This invention relates to improvements in locks for upwardly acting doors, such for example as sectional or multiple panel doors provided with tracks.

The main objects of this invention are:

First to provide a lock structure for upwardly acting doors which can be readily adjusted and installed at either the right or the left hand side of the door.

Second, to provide a lock structure for upwardly acting doors which may be readily installed and adjusted to the particular door.

Objects relating to details and economies of the invention will appear from the description to follow. The invention is defined and pointed out in the claims.

A preferred embodiment of the invention is illustrated in the accompanying drawing, in which:

Fig. 1 is a fragmentary front elevational view of an upwardly acting door embodying my invention, certain parts being shown conventionally.

Fig. 2 is an enlarged fragmentary view partially in vertical section on a line corresponding to 2—2 of Fig. 3.

Fig. 3 is an enlarged fragmentary view mainly in vertical section on a line corresponding to line 3—3 of Fig. 2.

Fig. 4 is a fragmentary view partially in vertical section on a line corresponding to line 4—4 of Fig. 3.

In the accompanying drawing 1 represents a wall of a building and 2 the floor thereof. The door illustrated is of the sectional or multiple panel type and comprises a plurality of panels 3 which are connected by hinges 4 arranged on the inner sides thereof. One of the hinge members of each pair is provided with bearings 5 for the spindles 6 of the track engaging rollers 7. The track 8 is provided with mounting brackets 9 disposed at the sides of the door opening.

The lock of my invention comprises a housing designated generally by the numeral 10 and including a rear wall 11, side walls 12, top wall 13 and front wall 14. The sides, rear and top wall may desirably be formed integrally of sheet metal as is illustrated. The rear wall 11 has a portion thereof struck forwardly to provide a bracket 15 which is disposed in spaced parallel relation to the top wall.

The top wall and the bracket have aligned pairs of holes 16 therein. These pairs of holes are transversely spaced and adapted to receive the pivot 17 for the bolt 18. The bolt is provided with an eye 19 through which the pivot is disposed. The pairs of holes 16 are located so that the bolt may be mounted to project through either of the bolt openings 20 in the side walls of the housing. These holes or openings 20 are substantially of greater width than the thickness of the bolt so the bolt may swing therein. The bolt is biased by the coil spring 21 which is arranged on the pivot and provided at one end with an arm 22 having a downwardly extending finger 23 engaging the front side of the bolt to bias the bolt rearwardly, the other end of the coil being provided with an arm 24 which engages the housing.

2

With this arrangement the bolt can be positioned to project through either opening to coact with the keeper 25 which may be mounted on the track 8 at either side of the door. The bolt is disengaged from the keeper by means of the release lever 26 which is pivoted at 27 on the pivot 28 arranged through the hole 29 in the side wall and the aligned hole 30 in one of the pair of pivot ears 31. This permits the lever to be positioned to coact with the bolt in either of its adjusted positions. The upper end of the lever engages the rear side of the bolt.

The plate like actuating member 32 is disposed below the front wall of the housing and provided with flange like arms 33 mounted by the pivots 34 on the inner sides of the side walls. The upper ends of these arms are provided with portions 35, one of which engages the lower end of the bolt release lever. The front wall terminating above the lower end of the rear wall permits the actuating member to be swung outwardly as illustrated by dotted lines in Fig. 3. The arms 33 are slotted at 36 to receive the stops 37 limiting the swing of the actuating member.

The actuating member is actuated by the push button 38 mounted to reciprocate in the socket 39 which is positioned in a bore 40 in the door. The bore 40 is located according to the mounting of the lock as a right or left hand lock and the rear wall 11 of the housing is provided with a pair of holes 41 through one of which the stem 42 of the push button projects to engage the actuating member 32.

A biasing spring 43 is arranged on the stem within the socket. The push button projects through an opening 44 in the escutcheon plate 45 which is desirably provided with a finger or hand piece 46 located below the push button so that it may be grasped to support the hand manipulating the push button and it also may serve as a hand piece for lifting the door.

The body 47 of the keeper is angled to embrace the track and has vertical slots 49 therein with which the securing bolts are engaged to support the keeper for vertical adjustment. The strike face 51 of the keeper is downwardly inclined so that as the door is closed the bolt strikes the face and is gradually swung forwardly, that is, forwardly relative to the housing until it is snapped under the keeper by means of its biasing spring 45. The details of mounting the housing are not illustrated but it is commonly mounted by means of screws.

The embodiment of the invention illustrated is adapted for mounting as either a right or left hand lock and this is desirable in upwardly acting doors as the lock should be positioned in the most convenient place for the particular installation. The structure avoids the necessity of making separate right and left hand locks to meet particular conditions.

I have illustrated and described the invention as applied to upwardly acting sectional doors. It will be understood that while it is particularly desirable for that type of installation, the door structure may be very considerably varied. The lock is adapted for varied types of upwardly acting door sections.

Having thus described the invention, what is claimed as new and is desired to be secured by Letters Patent is:

1. A lock for upwardly acting doors and the like comprising a housing including rear, top, side and front walls, the rear and side walls extending substantially below the front wall, a forwardly projecting bracket on the rear wall spaced from and parallel to the top wall, the top wall and bracket having laterally spaced pairs of aligned holes therein, the side walls having opposed bolt openings therein above said bracket, a bolt, a pivot for said bolt selectively engageable with either pair of holes in said top wall and bracket to swingably support the bolt with its swinging end projecting through one of said openings

in said side walls, a spring for biasing said bolt to keeper engaging position, a bolt release lever, pivot ears disposed on said rear wall below said bracket and in spaced relation to the side walls to selectively receive said release lever, said pivot ears and side walls having aligned pivot openings therein, a removable pivot for said bolt release lever, a release lever actuating member having flange like arms disposed on the inner sides of and pivotally mounted on the housing side walls with one of said arms coacting with said release lever in either of its adjusted positions, an escutcheon plate having a hand piece, a socket mounted in a bore in the door, a push button reciprocable in said socket and provided with a stem projecting through said housing rear wall to engage said actuating member, and a biasing spring for said push button arranged in said socket.

2. A lock for upwardly acting doors and the like comprising a housing including rear, top, side and front walls, the rear and side walls extending substantially below the front wall, a forwardly projecting bracket on the rear wall spaced from and parallel to the top wall, the top wall and bracket having laterally spaced pairs of aligned holes therein, the side walls having opposed bolt openings therein above said bracket, a bolt, a pivot for said bolt selectively engageable with either pair of holes in said top wall and bracket to swingably support the bolt with its swinging end projecting through one of said openings in said side walls, a spring for biasing said bolt to keeper engaging position, a bolt release lever, pivot ears disposed on said rear wall below said bracket and in spaced relation to the side walls to selectively receive said release lever, said pivot ears and side walls having aligned pivot openings therein, a removable pivot for said bolt release lever, a release lever actuating member having flange like arms disposed on the inner sides of and pivotally mounted on the housing side walls with one of said arms coacting with said release lever in either of its adjusted positions.

3. A lock for upwardly acting doors and the like comprising a housing including rear, top, side and front walls, the rear and side walls extending substantially below the front wall, a forwardly projecting bracket on the rear wall spaced from and parallel to the top wall, the top wall and bracket having laterally spaced pairs of aligned holes therein, the side walls having opposed bolt openings therein above said bracket, a bolt, a pivot for said bolt selectively engageable with either pair of holes in said top wall and bracket to swingably support the bolt with its swinging end projecting through one of said openings in said side walls, a spring for biasing said bolt to keeper engaging position, a bolt release lever, pivot ears disposed on said rear wall below said bracket and in spaced relation to the side walls to selectively receive said release lever, said pivot ears and side walls having aligned pivot openings therein, a removable pivot for said bolt release lever, a release lever actuating member having flange like arms disposed on the inner sides of and pivotally mounted on the housing side walls with one of said arms coacting with said release lever in either of its adjusted positions, said arms having slots therein, and stops on said side walls coacting with said slots to limit the outward swing of the actuating member.

4. A lock comprising a housing having bolt openings in opposite sides thereof and having a bolt supporting bracket therein, a bolt provided with a pivot positionable on said bracket to support the bolt in position to project through a selected one of said bolt openings, a spring for biasing the bolt to keeper engaging position operatively associated with the bolt and its pivot for adjustment therewith, a bolt release lever disposed within said housing

5 provided with a pivot adjustably positionable on the housing to support the release lever in coacting relation to the bolt in its adjusted position, an actuating member for said release lever pivotally mounted on said housing and provided with means engaging the release lever when it is positioned in either of its mounted positions, means for limiting the swinging movement of said lever actuating member, a push button socket, a push button reciprocable in said socket and provided with a stem projecting into the housing to engage said actuating member, and a biasing spring for said push button disposed in said socket.
